MOISTURE RESISTANT VALVE BAG

John A. Rosmait, Manistee, Mich.

Application April 26, 1935, Serial No. 18,313

4 Claims.

(Cl. 150—9)

My invention relates to improvements in moisture resistant valve bags.

An object is to provide a moisture resistant valve bag which is so constructed that while it is moisture resistant it is also adapted to permit the escape of air through a provided air permeable portion of the bag wall during the filling of the bag.

A further object is to provide a bag the major portion of the wall of which is characterized in that it is impervious to air and to moisture, but which bag has a minor portion of its wall formed of material which is permeable to air but impervious to moisture whereby the bag as a whole is moisture resistant but has a limited wall area which, while it is moisture resistant, is air permeable to permit the escape of air from the interior of the bag during the filling of the bag.

Another object is to provide a bag of the multi-wall paper type which is moisture resistant and wherein the characteristic which provides its resistance to moisture prevents the filtration of air through the bag wall, but which bag has a wall area of limited extent which is so constructed as to be resistant to moisture but is permeable to air. In the construction here shown this limited air permeable portion is illustrated as located at one end of the bag. Preferably each side wall is provided with a limited end portion of this structure and the bag walls are secured together at such end through said air permeable portions. The bag filler opening is likewise preferably located between those wall portions which are air permeable.

An important feature is that the air permeable portion of the bag walls, which portion is water and moisture resistant, is formed of a tough, strong, material such as suitably prepared fabric, which is securely attached to the major portion of the bag walls and serves as a continuation thereof at one end of the bag. The bag walls are secured together through these air permeable portions in such a manner as to facilitate the opening of the bag at such end for discharge of its contents. The bag may be again sealed at such end by fastening means extending through such air permeable portions, such portions possessing sufficient strength and ruggedness to permit of re-use to receive the fastening means a plurality of times.

The bag may be provided with a hand grip aperture extending through the strong air permeable woven portions of its side walls, such portions being secured together surrounding said

hand grip aperture whereby the bag is more readily adaptable for handling.

Other objects, advantages, and meritorious features of my invention will more fully appear from the following specifications, appended claims, and accompanying drawing, wherein:

Figure 1 is a side elevation of a fragment of a bag embodying my invention wherein the bag is partly broken away to show its construction,

Fig. 2 is a cross-sectional view taken on line 2—2 of Fig. 1,

Fig. 3 is a side elevation of a fragment of a bag embodying my invention, but of a modified form as compared with Fig. 1, and wherein one wall of the bag is broken away,

Fig. 4 is a cross-sectional view taken on the line 4—4 of Fig. 3,

Fig. 5 is a perspective of a bag embodying a modification of my invention, and

Fig. 6 is a side elevation of a fragment of a bag with one wall partly broken away wherein the bag embodies my invention and is provided with a feature additional to that shown in Fig. 1.

My invention relates to that type of bag which is moisture resistant and wherein the moisture resistant wall portion is substantially impervious to the passage of air as a result of its moisture resistant characteristic. These bags are commonly formed of multi-ply paper.

One method of waterproofing the same is to provide a water resistant ply which may be accomplished by coating one ply with suitable water resistant material, such as asphalt latex or the like or such ply may be formed of some suitable metallic foil which is impervious to moisture. If desired, the laminated wall may contain a single ply which is inherently moisture resistant. My invention also pertains to bags of the valve type. These bags are commonly used to contain powdered material. This material is deposited in the bag through the valve opening. The air within the bag is exhausted during the deposit of the content material therein. In a common paper bag the air filters out through the paper wall. The waterproof layer is normally impervious to the passage of air and prevents the discharge of air therethrough.

I provide a bag of this type with a wall portion of limited extent which is adapted to permit the flow of air therethrough but is moisture resistant. Certain types of waterproof fabrics possess these characteristics. They would be too expensive to use for the manufacture of bags but I employ only a relatively small portion of such material in each bag.

In the construction shown there is illustrated

35

55

a bag having a side wall 10. This side wall is preferably formed of several layers of paper 12. One of these layers 14 may be rendered waterproof through the application of asphalt or other moisture resistant material thereto. In the several figures, with the exception of Fig. 1, the laminated character of the wall is not illustrated but this is for the purpose of simplifying the drawing and it is to be understood that while the wall need not necessarily be laminated that this is a satisfactory form of construction and the wall is rendered moisture resistant and is substantially impermeable to air.

In the bags illustrated in Figs. 1, 3, and 6 there is provided a filler opening 16 formed by turning in corner portions of the side walls and through which the filler spout of filling mechanism may be inserted to fill the bag.

In Figs. 1 and 6 and subsidiary Figs. 2, 4, and 5, the bag is shown as provided at one end with a wall portion formed of moisture resistant air permeable fabric or the like 18. In Figs. 1 and 6 this fabric is shown as an extension of each side wall and the two portions are shown as stitched together along the line 20 to close the end of the bag. In the construction shown in Fig. 5 this fabric is shown as continuous and extends from one wall portion 10 of the bag to the opposite wall portion being stitched thereto as at 22. Figs. 1 and 2 show reinforcement strips 24 secured underneath the line of stitching and reinforcement strips might be provided if desired for the line of stitching 20.

In Figs. 1 and 6 the valve structure is formed in this air permeable portion, the corners being turned in as indicated at 16 for this purpose. Fig. 6 illustrates a hand grip aperture 24. The material 18 is stitched at 26 around this aperture enclosing a cord 27 to provide a good gripping margin. During the filling of the bag as the powdered content material enters through the valve filler opening 16 the air escapes through the foraminous portion 18. This portion, however, is moisture proof so as to protect the material within the bag.

Fig. 3 shows a construction wherein the turned corners 16 which form the valve opening are integral parts of the side wall elements 10 and a separate valve member 28 is provided. This valve member is formed of sheet material folded as indicated in Fig. 3 to form a tubular extension of the turned corner portion 16 and is held in place by the line of stitching 20 which secures the two side walls of the bag together across the end. This tubular extension 28 is shown as slitted at 30 to facilitate the discharge of the content material into the interior of the bag.

To provide an escape for the air the opposite corners of the side walls of the bag may be cut away as at 32 and a sheet of air permeable moisture resistant fabric or other suitable material may be stitched therein to fill out such cut away portion. The line of stitching is indicated as 34. This provides a bag wherein in the corner opposite to the valve filler opening corner there is a foraminous portion which permits the escape of air.

One well known method of treating woven fabric so that it is rendered waterproof and yet remains impervious to air would be to first wash the fabric with a hot, weak solution of alkali which is afterwards removed by washing with hot water and drying. The fabric is then immersed in a hot mixture of white paraffin wax and cotton oil to which are added resin and oil of turpentine. It is then passed through a wringing machine after which it is tried at a temperature not to exceed 120° F.

What I claim:

1. A valve bag having its side walls except for a short distance at one end formed of substantially imperforate moisture resistant material, said short end portion being formed of air permeable and moisture resistant material, and said bag having its valve opening arranged within said air permeable moisture resistant wall portion.

2. A valve bag having the major portion of each side wall formed of imperforate water resistant material and a minor portion of each side wall at one end of the bag formed of air permeable water resistant material, said bag walls being secured together at such end by a line of stitching extending through said air permeable portions of the side walls, said bag having a valve opening in one corner between said air permeable portions of its side walls.

3. A bag having a wall the major portion of the area of which is formed of material substantially impervious to air and moisture, said wall having a minor portion of its area at one end formed of material pervious to air but substantially impervious to moisture, said bag having a valve filler opening located at said end.

4. A bag of the valve type having the major portion of each side wall formed of multi-ply wall paper substantially impervious to air and moisture, each side wall having one corner portion formed of air permeable moisture impervious material and having its opposite corner portion at the same end of the bag turned into the bag forming a valve filler opening.

JOHN A. ROSMAIT.
